UNITED STATES PATENT OFFICE

ROBERT F. RINGLE, OF ZELIENOPLE, PENNSYLVANIA

MOLDING MACHINE

Application filed December 5, 1927. Serial No. 237,629.

My invention relates to improvements in molding machines of the type used for agitating a mold and its flask for jarring, so as to tamp the sand evenly and compactly around the pattern.

The machine is generally similar to that shown in prior patent of Herman et al. #908,002 issued December 29, 1908.

The present improved construction has in view to provide means, combined with a main fluid pressure line, for distributing lubricant to various working parts of the machine; also to means providing for maintaining the working table in vertical alignment with the supporting base, with lubrication for the working parts and to other features of detail construction, as shall be more fully hereinafter described.

Generally stated, the machine comprises a foundation base or frame having a centrally arranged cylinder, a vibrating table provided with a plunger mounted in the cylinder, an automatically operating valve for admitting and releasing pressure to and from the cylinder for alternate operation of the plunger and table, guiding means at the corner portions of the frame and table, and the parts comprising the fluid supply and lubricating system, as more fully hereinafter described.

Referring to the drawings, showing one preferred embodiment of the invention:—

Fig. 1 is a view partly in vertical section and partly in elevation showing the complete machine, in lowered position;

Fig. 2 is an enlarged sectional detail view on the line II—II of Fig. 4;

Fig. 3 is a sectional detail view on the line III—III of Fig. 4, showing the application of lubricant to the plunger cylinder;

Fig. 4 is a view partly in horizontal section and partly in plan of the complete machine, the upper sectional portion being indicated by the line IV—IV of Fig. 1.

The main base portion 2 of the machine

consists of a rectangular casting adapted to be mounted on a suitable supporting foundation 3, in which base is centrally carried the cylinder 4 or a vertically reciprocating plunger 5. The cylinder 4 is located within a central annular cavity of the main base 2 depending therefrom by an upper annular flange 6, by which it is secured by any suitable means, as bolts. The base 2 is amply braced and supported by interior and exterior ribs and partitions, the interior partitions and the table supporting floor being provided with transverse openings 7 for air circulation, whereby to allow for ample incoming and outgoing air and avoiding objectionable partial vacuum, due to the rapid reciprocation of the jarring table.

The outer portion of the base extends upwardly above a middle transverse floor portion 8 by outer walls 9, between which the jarring table 12 extends downwardly for bumping action against an intervening transverse jarring plate 10. The latter is laid across the middle floor portion 8 of the machine with middle clearance for the plunger cylinder, and with an intervening comparatively thin sheet 11 of suitable shock absorbent material, as fibre, cork, or other resilient material, whereby to absorb the shocks of impact.

The jarring table 12 extends across the entire upper portion of the supporting base frame by its upper table top and is provided with a downwardly extending interior skeleton framework 13. The latter is provided with a supporting bottom 14 adapted to make contact with the jarring plate 10, and is alternately raised by the plunger 5 and lowered by gravity, upon admission and exhaust of a suitable fluid under pressure. The middle interior portion of the table 12 is provided with an annular frame or ring 15, against which abuts and to which is secured the upper flange 16 of the plunger 5.

The plunger is alternately raised and low-

ered by admission of fluid under pressure through the valve A, with exhaust there-through upon gravitating return of the table. The stem of the valve is lifted and lowered by the connecting yoke or bunter stem 17 of the valve secured as at 18 in the lower body portion of the table at one side of the plunger cavity.

The stem 19 of the valve is connected with the cylindrical slide valve 20 by its terminal 10 having the nut 21 and collar 22 providing for a limited amount of lost motion at each side of the middle hub 23 of the valve.

The stem 17 being connected with the table will rise with the rise of the table under pressure, cutting off the pressure supply through inlet pipe B and opening the exhaust ports for escape of the previously used pressure fluid through exhaust pipe C, upon alternate lowering of the table.

Likewise, lowering of the table after a limited amount of lost motion of stem 19, will shift the valve 20 downwardly, closing the exhaust ports and opening the supply for another lifting operation.

The corner wall portions 9 of the main base provide outer guiding housings for the table, which is provided at each corner with the wearing faces 24, planed at right angles to each other and providing for vertical guiding movement within co-acting wearing plates 25. The wearing plates 25 are mounted within the upwardly extending corner wall portions 9 by means of series of upper and lower studs and bolts 26—27 respectively. The contacting faces of such plates with the corner faces 24 of the table are accurately fitted for vertical sliding movement, one against the other, during vertical reciprocation of the table throughout its limited range of movement.

For the purpose of protecting the interior of the construction and preventing access of dust or other foreign matter to such wearing faces, I provide outer enclosing covering plates 28 of thin sheet or plate metal, bolted or otherwise secured to the edges of table 12, extending downwardly over the outer portion of walls 9 so as to slide thereon with a close fit, effectually excluding such objectionable impure air circulation.

For the purpose of lubricating the working faces at the corner of the machine, and also the plunger cylinder, I provide the system of distributing pipes and pressure mechanism whereby a suitable lubricant is distributed to such various working parts, as shown in the drawings.

For such purpose, a main lubricant containing reservoir 29 is connected by a branch pipe 30 to the main air or other fluid supply line 31, so as to exert pressure on the lubricant reservoir when the fluid supply is admitted by operating valve 32 thereof.

Reservoir 29 is provided with branch sup-

ply pipes 33 and 34 respectively, each having an opening and closing control valve 35 and 36, respectively. Pipe 33 is connected with a main annularly arranged supply pipe 37 extending entirely around the machine, as shown in Fig. 4. At suitable intervals, branch supply conduits, preferably in the form of sections of rubber hose 38, extend from pipe 37 upwardly to a point opposite the middle of each of the wearing plates 25, as in Fig. 2. The branch connections 38 are each provided with a terminal pipe 39 extending inwardly through the outer wall 9 and through the wearing plate 25, or an opening therein, so as to furnish lubricant through its reduced terminal between it and the outer wear faces 24, at each corner portion, as clearly shown. With such arrangement, the lubricant will be furnished under pressure equally to all of the several points of application during the time that air pressure is exerted on reservoir 29 while the machine is being operated.

Likewise, for the purpose of supplying lubricant to the interior of cylinder 4, branch pipe 34 extends inwardly through the plunger casing, as at 40, providing for lubricant under pressure during the operative period.

It will be understood that the flow of lubricant may be accurately controlled by valves 35 and 36 and that suitable lubricant as to its fluidity should be utilized to maintain the working parts in proper lubricated condition.

With the machine operating in the manner intended with continuous alternating vertical reciprocations and with the accurate action of the guiding means provided, the lubrication of the parts greatly facilitates its continuous efficient operation, avoiding wear, and with incidental protection of the parts from intrusion of sand or other gritty foreign material.

What I claim is:—

1. The combination with a jarring machine having a supporting floor and a surrounding upwardly extending rectangular wall, wear plates mounted in the corner portions of the wall, a reciprocable table within the wall having corner portions engaging the wear plates, an isolated lubricant reservoir, a lubricant conduit surrounding the machine connected with the reservoir and having branch connections leading inwardly through the wear plates, and means providing for pressure on the contents of the reservoir.

2. The combination with a jarring machine having a supporting floor and a surrounding upwardly extending rectangular wall, wear plates mounted in the corner portions of the wall, individual supply pipes leading inwardly through the wear plates, a reciprocable table within the wall having

corner portions engaging the wear plates, a lubricant reservoir, a lubricant conduit surrounding the machine connected with the reservoir by a valve regulated pipe and having flexible branch connections with said supply pipes, and means providing for pressure on the contents of the reservoir.

3. The combination with a jarring machine having a supporting floor and a surrounding upwardly extending rectangular wall, independent wear plates mounted in the corner portions of the wall, a plunger casing extending below the floor, a fluid supply and exhaust valve connected with the casing, a reciprocable table within the wall having corner portions engaging the wear plates and a plunger extending into the casing, a lubricant reservoir, a lubricant conduit surrounding the machine connected with the reservoir and having branch connections leading inwardly through the wear plates, and a fluid supply conduit connected with the valve and with the lubricant reservoir.

4. The combination with a jarring machine having a supporting floor and a surrounding upwardly extending rectangular wall, independent wear plates mounted in the corner portions of the wall, a plunger casing extending below the floor, a fluid supply and exhaust valve connected with the casing, a reciprocable table within the wall having corner portions engaging the wear plates and a plunger extending into the casing, a lubricant reservoir, a lubricant conduit surrounding the machine connected with the reservoir and having branch connections leading inwardly through the wear plates, a lubricant conduit connected with the plunger casing, and a fluid supply conduit connected with the valve and with the lubricant reservoir.

5. The combination with a jarring machine having a supporting floor and a surrounding upwardly extending rectangular wall, independent wear plates mounted in the corner portions of the wall, a plunger casing extending below the floor, a fluid supply and exhaust valve connected with the casing, a reciprocable table within the wall having corner portions engaging the wear plates and a plunger extending into the casing, a lubricant reservoir, a lubricant conduit surrounding the machine connected with the reservoir and having branch connections leading inwardly through the wear plates, a lubricant conduit connected with the plunger casing, a control valve in each of said conduits, a fluid supply conduit connected with the valve, and a branch conduit connecting said conduit with the lubricant reservoir.

6. The combination with a jarring machine having a supporting floor and a surrounding upwardly extending rectangular wall, independent wear plates rectangularly arranged in pairs and mounted in the corner portions of the wall, a reciprocal table with-

in the wall having corner portions engaging the wear plates, an isolated lubricant reservoir, a lubricant conduit surrounding the machine connected with the reservoir and having branch connections leading inwardly through the wear plates, and means providing for pressure on the contents of the reservoir.

In testimony whereof I hereunto affix my signature.

ROBERT F. RINGLE.
